UNITED STATES PATENT OFFICE.

WILLIAM KERR, OF PHILADELPHIA, PENNSYLVANIA.

FEED-WATER HEATER AND PURIFIER FOR BOILERS.

SPECIFICATION forming part of Letters Patent No. 447,881, dated March 10, 1891.

Application filed November 6, 1890. Serial No. 370,458. (No model.)

To all whom it may concern:

Be it known that I, WILLIAM KERR, a citizen of the United States, residing in the city and county of Philadelphia, State of Pennsylvania, have invented a new and useful Improvement in Feed-Water Heaters and Purifiers for Boilers, which improvement is fully set forth in the following specification and accompanying drawings.

10 My invention consists of a feed-water heater and purifier having a tank with an outlet-pipe leading therefrom below the opening of the inlet-pipe, and a series of outlet communicating pipes open at one end.

15 Figure 1 represents a partial side and partial sectional view of a feed-water heater and purifier embodying my invention. Fig. 2 represents a horizontal sectional view of the device on line xx , Fig. 1.

20 Similar letters of reference indicate corresponding parts in the two figures.

Referring to the drawings, A designates a pipe leading from a supply into the top of a tank B, which latter is provided with a pipe 25 C, having its upper end open and enlarged, and above the opening of the pipe A, and its lower end leading from the tank and provided with the blow-off cock D. The tank B is also provided with a waste-pipe D', having 30 a blow-off cock E. An outlet-pipe F, having one end inserted in the tank B, so as to lead from the middle portion thereof, enters the boiler G and connects with the series of pipes H J, which extend nearly the length of 35 the boiler, and are located within the water-receptacle of the same, a short distance from the bottom thereof. The ends of the pipes H J are in communication by means of short pipes K and L. A pipe M leads from the 40 lower rear end of the boiler and is provided with a blow-off cock N.

In operating the device the feed-water, which may be first heated in any ordinary heater, if desired, is passed through the pipe 45 A into the tank B, where the grease or other scum in the same rising to the surface is carried off by the pipe C, and the dirt or sediment which settles in the bottom of the tank is drawn through the waste-pipe D' by means 50 of the blow-off cock E. The water at the middle portion of the tank B enters the pipe F and is carried into and through the pipes H and J in the boiler G, the heat of the wa-

ter in the latter heating the water in the said pipes to such a temperature that the dirt 55 and impurities therein are freed therefrom, and, being carried to the rear end of the said pipes, are deposited in the lower portion of the rear end of the boiler, so as to be readily forced out through the waste-pipe M by means 60 of the blow-off cock N, thus purifying and heating the water fed to the boiler. It will be noticed that by having the open end of the outlet-pipe F leading from the middle portion of the tank and the scum-discharge 65 pipe C opening above the same the scum or grease is effectually prevented from entering the pipe F, and thereby the boiler.

Having thus described my invention, what I claim as new, and desire to secure by Letters 70 Patent, is—

1. A feed-water heater and purifier consisting of a tank with inlet and outlet pipes, said outlet-pipe leading upward from within the tank below the opening of the inlet-pipe, 75 and a series of pipes, each of which is in communication at one end with said outlet-pipe and open at the other end, said parts being combined substantially as described.

2. A feed-water heater and purifier consisting of a tank with an inlet-pipe, an outlet-pipe leading into the upper part thereof, leading from the middle portion of said tank, having an enlarged upper end above the openings of the inlet and outlet pipes, a scum-discharge pipe below the opening of the inlet-pipe and a waste-pipe, a series of pipes 85 communicating at one end with said outlet-pipe and open at the other end, a boiler in which said series of pipes are located, and a waste-pipe leading from the boiler at the end thereof where the open ends of the series of pipes are located and provided with a blow-off 90 cock, said parts being combined substantially as described.

3. A feed-water heater and purifier having a tank with inlet and outlet pipes and a scum-separating device, and a series of pipes, each communicating with the said outlet-pipe at one end and open at the opposite end, said parts 100 being combined substantially as described.

WILLIAM KERR.
